HAND NAILER

Lars Frostad, Syracuse, and Heiko T. de Man, Liverpool, N.Y., assignors, by mesne assignments, to The Porter-Cable Machine Company, Syracuse, N.Y., a corporation of Delaware

Filed Dec. 3, 1959, Ser. No. 857,184

4 Claims. (Cl. 1—46)

This invention relates to nail drivers of the type wherein nails are automatically and successively fed to a nail discharge passage, the nails being driven through the discharge passage into the work piece by downward movement of a plunger and nail driving blade carried thereby, the downward movement of the plunger being effected by being struck by a hammer, or mallet.

Nail drivers of this type are used, for example, in the laying of hardwood floors. They are equipped with magazines containing a substantial supply of nails, all whereby the nails are driven more rapidly in the most suitable part of the work piece, or floorboard, and are driven with less effort.

This structure has as an object a nail driver embodying a magazine structure which is convenient to load and which functions efficiently to successively deliver nails to the nail delivery passage.

The invention has as a further object a full stroke mechanism to prevent upward or return movement of the driving plunger until the nail being driven has been driven home, this mechanism embodying a structure which is entirely reliable and free from maintenance, and economical to construct.

The invention consists in the novel features and in the combinations and constructions hereinafter set forth and claimed.

In describing this invention, reference is had to the accompanying drawings in which like characters designate corresponding parts in all the views.

In the drawings—

FIGURE 1 is a side elevational view of a nail driver embodying our invention.

FIGURE 2 is a view, similar to FIGURE 1, with one side of the body broken away, and one side of the nail magazine removed, and with the forward or head portion of the device shown in vertical section.

FIGURE 3 is a comparable view to the upper right portion of FIGURE 2 but showing the driving plunger in down position.

FIGURE 4 is a view, similar to FIGURE 3, showing the plunger in partially downward position.

FIGURE 5 is a transverse sectional view taken on a line corresponding to line 5—5, FIGURE 2.

FIGURE 6 is a side elevational view with one side of the body broken away, the magazine being shown in side elevation and positioned in the magazine chamber.

FIGURE 7 is a view, similar to FIGURE 6, with the magazine moved to open loading position.

FIGURE 8 is a front end elevational view of the shear plate, the view being taken as indicated by line 8—8, FIGURE 2.

FIGURE 9 is a view taken on a plane corresponding to line 9—9, FIGURE 2.

FIGURE 10 is a view taken on line 10—10, FIGURE 2.

FIGURE 11 is a view taken on a plane corresponding to line 11—11, FIGURE 2.

FIGURE 12 is a view taken on line 12—12, FIGURE 11.

FIGURE 13 is an elevational view of the lower portion of the front surface of the plunger, and

FIGURE 14 is a top plan view of the pawl employed in the full stroke mechanism.

2

The nailer consists of a body formed of two similar parts 20, 21, formed at their forward ends with upwardly extending projections 22, 23, to provide a head portion. The parts 20, 21, extend rearwardly from the head portion to a rear portion 25, which curves upwardly and forwardly to form a handle 26. The body parts 20, 21, are spaced apart throughout their intermediate portions to form a magazine receiving chamber 27 extending rearwardly from the head portions 23 to the rear portion 25.

10 This chamber 27 is for the reception of a nail magazine which is here shown in the form of two similar parts 30, 31, the upper edges of which are formed with flanges 32 secured together as by rivets 33 forming a top rib projecting upwardly between inwardly extending flanges 36, see FIGURE 5, formed on the upper edges of the body parts 20, 21.

The confronting sides of the parts 30, 31, are formed with grooves 37 to receive the heads 38 of the nails 40, the nail heads being supported on ribs 41. Below the ribs 20 41, the parts 30, 31, are formed with rectangular grooves 43 of substantial dimension to provide a rectangular passageway 44 to slidably receive a pusher 45. The bottom walls of the grooves 43 terminate in spaced apart relation to provide a slot for the passage of a handle 46 which is bent to extend laterally through a slot 47 formed in the body piece 20, the handle having a cylindrical portion 48 extending laterally from the side of the body with which the pusher 45 can be conveniently retracted, or moved rearwardly, against the action of a spring 50 which 25 extends rearwardly up into the handle portion 26, see FIGURE 2, and is captivated by a plug 51. The pusher 45 and spring 50 serve to yieldingly advance the nails 40 forwardly along the guideway toward the head portion.

The forward end of the magazine is mounted upon 35 pivot pins 52 in the form of dog point screws threaded into the body members 20, 21. The forward ends of the magazine parts 30, 31, are inclined, as at 55, to permit the magazine to be moved downwardly about the pivot 52 to the open position shown in FIGURE 7. The pusher 45, when retracted to the rear portion 25, is retained in retracted position by a latch 57 pivoted in the body parts, as at 58, and having a hook end 59 engaging a downwardly extending projection 60 on the under side of the pusher 45. The latch is urged to latching position by a 40 spring 61, see FIGURES 6 and 7.

Means is provided for detachably holding the magazine in the chamber 27. As shown in FIGURES 2, 6 and 7, a latch pin 63 is mounted in the rear body portion 25 for axial movement, the pin being urged forwardly by a 45 compression spring 64 to position the forward end of the pin into the upper portion 37 of the nail guide plate. This effects a releasable means for holding the magazine in the magazine receiving chamber and with the nail guideway arranged in alignment with the nail discharge passage 50 hereinafter referred to. The latch pin 63 is formed with a collar 67 against which the spring 64 acts. The pusher 45 is formed with an upwardly extending projection 68 so arranged that when the pusher is moved to retracted position, as shown in FIGURES 6 and 7, the projection 68 engages the collar 67, moving the latch pin 63 rearwardly out of engagement with the magazine. The latch 55 63 is released from the pusher by pressing inwardly on the tail portion 69 of the latch 57. In order to prevent accidental release of the pusher when the magazine is in the loading position shown in FIGURE 7, the rib portions 32 of the magazine parts are formed at their rear ends with upwardly extending projections 70 and are so dimensioned that when the magazine is in open position, the projections 70 provide an interference to prevent forward movement of the pusher 45. For devices of this 60 type, the nails are usually severally attached together by 70

glue, so that the nails are handled in stick form for loading the magazine.

The forward ends of the body parts 20, 21, terminate short of the forward edges of the upwardly extending projections 22, 23, and there is positioned on the forward ends of the body parts a shear plate 72. This plate is formed with a slot 73 extending upwardly from its lower edge and communicating with an elliptical shaped aperture 74. The upper portions of the magazine slide parts 30, 31, above the recess 44, extend forwardly as at 75 and, in like manner, the nail supporting ribs 41 extend into the opening 74 of the shear plate and terminate flush with the forward side of the plate, all this when the magazine is positioned in the chamber 27, as shown in FIGURES 2 and 6, whereby the nails are advanced along the ribs 41 and through the slot 73 in the shear plate 72 and into the nail delivery passage 80.

A nose piece 81 overlies the shear plate 72 and is formed with side flanges 82 abutting the ends of the body parts 20, 21, and extending along the side edges of the plate 72. The nose piece 81 is fixedly secured to the members 20, 21, by screws 83 extending through apertures 84 in the shear plate and being threaded into the members 20, 21. The nose piece is formed with the vertically disposed nail delivery passage 80.

The upwardly extending portion, formed by the portions 22, 23, of the body members, is formed with a square passageway in which there is mounted two U-shaped members 86, 87, having their side flanges abutting and being formed of wear resistant metal to provide a bushing in which the plunger 88 is slidably mounted. The plunger is formed on opposite sides with lengthwise extending recesses 89. The members 22, 23, are formed to provide vertically elongated apertures 90 which extend transversely of the axis of the plunger 88 and communicate with grooves 91 extending in a direction axially of the plunger in adjacency to the bushing members 86, 87. Members 93 are slidably mounted in the recesses 91. The lower ends of these members are provided with transversely extending threaded apertures to receive screws 94, the heads of which are positioned in the apertures 90, the screws having inner portions 95 of reduced diameter extending into the grooves 89 formed in the sides of the plunger 88. These screws terminate short of the bottom whereby, when the plunger is in the up position as shown in FIGURES 1 and 2, the inner ends 95 of the screws 94 are engaged by the bottom of the slots 89. The members or blocks 93 are slidably mounted in the recesses 91 and are urged downwardly by compression springs 97. This arrangement provides a yieldable bumper when the plunger is returned to up position by the compression spring 98 which encircles a guide rod 99, the spring extending upwardly in an axially extending hole 100 formed in the plunger 88.

The forward side of the plunger 88, see FIGURE 13, is formed at its lower end with a groove 101 extending upwardly from the lower edge of the plunger and communicating with a circular recess 102. A nail driving blade 103 is formed at its upper end complementary to the recesses 101, 102, and depends from the plunger with the lower end of the blade 103 positioned just above the nail delivery passage 80 when the plunger is in its up position, see FIGURE 2. When the plunger 88 reaches the bottom of its stroke, the lower end of the blade 103 is positioned at the bottom of the passage 80 and the nail is driven home.

Means is provided to prevent upward movement of the plunger 88 by the spring 98 until the plunger has reached the bottom position and the nail has been driven home. This permits the operator to apply more than one hammer stroke to the plunger head 114 in the driving of a nail without having the plunger return to up position, which might result in the next nail in the magazine being jammed in the passage 80 partially occupied by the partially driven nail.

This structure consists in the plunger 88 being formed on its rear side with a surface 116 confronting a pawl 108 mounted in the head portion 23 of the machine. The surface 116 has a vertical or lengthwise dimension of the plunger such that it is engaged by the pawl when the plunger is intermediate its up and down positions. The lower end of this surface 116 is defined by a recess 104, and the upper end of the surface is defined by a recess 106. As illustrated in FIGURE 2, with the plunger 88 in its up position, the surface 116 is positioned above the pawl and, as illustrated in FIGURE 3, with the plunger in its down position, the surface 116 is positioned below the pawl.

The body members 22, 23, are formed in their confronting sides in the head portion of the machine with concavities 107 in which the pawl 108 is mounted. This pawl is formed with trunnions 109, see FIGURE 14, journalled in bushings 110. This pivot point is spaced laterally from the surface 116 of the plunger 88 such that the free end 111 of the pawl will engage the surface 116 prior to the pawl assuming a position normal to the plunger. In other words, the engagement of the pawl with surface 116 is cant-fashion, as shown in FIGURE 4. As illustrated in FIGURES 2, 3 and 4, the pawl 108 is urged to a position normal to the axis of the plunger by leaf springs 112 positioned in the recess 107, the pawl being shown in such position in FIGURE 4.

As the plunger moves downwardly, the lower edge of the surface 116 engages the pawl and moves it downwardly about its pivot 109, the plunger passing freely downwardly. However, the pawl has now been canted, as shown in FIGURE 4, whereby any retrograde or upward movement of the plunger is prevented by the pawl. When the plunger has reached the bottom of its stroke and the nail has been driven home, the surface 116 has passed below the area in which the pawl is mounted and the upper recess 105 provides space for the pawl to again assume position normal to the plunger. The pawl does not interfere with upward return movement of the plunger from its down position. As the plunger moves upwardly under the influence of the spring 98, the free inner end of the pawl will be engaged by the upper end of the surface 116, and the pawl will be canted upwardly so that it does not bind the plunger upon its upper return movement.

In the modified form shown in FIGURE 15, the pawl is pivotally mounted in a bearing yieldingly mounted in the machine for movement in a direction laterally from the plunger 88. Such an arrangement can be economically provided by mounting the bearing bushing 110 in a block 118 of yieldable material such as rubber. The block 118 is mounted in concavities 119 similarly located to the concavities 107 in the arrangement previously described. This block 118 may also function to yieldingly urge the pawl 108 in position normal to the axis of the plunger, this being accomplished by forming the block 118 with upper and lower lip portions 120 extending inwardly toward the plunger for engaging the pawl after the manner of the springs 112 in FIGURE 4. This pivotal mounting of the pawl for yielding movement in a direction away from the plunger avoids the precision machining and mounting of the pawl pivot as in the arrangement shown in FIGURES 2, 3 and 4. This yielding movement of the pawl pivot also provides for the release of the pawl in the event it should become jammed against the plunger. The yieldable mount being sufficient for the full stroke control of the plunger in normal operation but being yieldable to release the plunger in the event of jamming.

In operating the nailer, the pusher 45 is moved to the rear portion 25 of the body by means of the handle 48. The pusher is retained in this rear portion by the latch 57. This movement of the pusher into latched position releases the restraining pin 63 whereupon the magazine may be moved downwardly out of the body about the pivot 52 to the position shown in FIGURE 7. In this position, a row of nails can be conveniently inserted in the guideway

of the magazine. The magazine is then moved into the body and the pusher released by pressing upwardly on the tail portion 69 of the latch 57.

The pusher is advanced forwardly against the row of nails by the spring 50, and forward movement of the pusher releases the retaining member 63 for engagement with the rear end of the magazine, thus restraining movement of the magazine out of the body. The nails are driven by blows applied by the knob 114 on the blade driving plunger.

We claim:

1. A nail driver comprising an elongated body having an upwardly extending head portion at its forward end and a rearward portion, said head portion being formed with a nail delivery passage, said body being formed with an elongated chamber extending rearwardly from said head portion to said rear portion, a nail magazine movable into and out of said chamber and having a nail guideway in registration and communicating with said delivery passage when said magazine is positioned in said chamber, a pusher slidably mounted in said guideway, a spring for urging said pusher along the guideway toward said head portion to advance a row of nails along the guideway toward said delivery passage, releasable means for restraining movement of said magazine out of said chamber, said pusher being retractible from said magazine into said rear portion of the body, and releasable latch means for holding said pusher in retracted position in said rear portion of the body.

2. A nail driver comprising an elongated body having an upwardly extending head portion at its forward end and a rear portion, said head portion being formed with a nail delivery passage, said body being formed with a magazine receiving chamber extending rearwardly from said head portion to said rear portion, a nail magazine moveable into and out of said chamber and having an elongated nail guideway in registration and communicating with said delivery passage when said magazine is positioned in said chamber, a pusher slidably mounted in said guideway, a spring for urging said pusher forwardly along the guideway toward said head portion to advance a row of nails along the guideway to said delivery passage, said pusher being retractible from said magazine into said rear portion of the body, means carried by said rear portion and movable into engagement with said magazine to retain the same in said chamber, a releasable latch means mounted in said rear portion and movable into latching engagement with said pusher for holding the same in retracted position, said pusher being operable in retracted position to move said magazine retaining means out of engagement with said magazine.

3. A nail driver comprising an elongated body having

an upwardly extending head portion at its forward end and a rear portion, the intermediate portion of said body being formed with an elongated magazine receiving chamber, said head portion being formed with a nail delivery passage, a nail magazine pivotally secured at its forward end to said head portion for movement about said pivot into said chamber and out of said chamber to loading position, said magazine having a nail guideway aligned and communicating with said nail delivery passage when the magazine is moved into said chamber, a pusher slidably mounted in said nail guideway, and a spring cooperating with said pusher for urging the same forwardly along the guideway toward said head portion to advance a row of nails along the guideway for delivery to said delivery passage, said pusher being retractible from said magazine into said rear portion of the body, said magazine having means operable when the same is moved to outward loading position to prevent forward movement of said pusher from said rear portion of the body.

5 4. A nail driver comprising a body having an upwardly extending head portion at its forward end formed with a nail delivery passage, a magazine structure for feeding nails to said passage, a plunger slidably mounted in the head portion and having a depending nail driving blade 10 for movement downwardly through said passage upon downward movement of the plunger to down position to drive a nail through said passage into a work piece, a spring for effecting an upward return movement of said plunger to its up position, a bearing mounted in said head 15 portion for lateral movement in a direction from said plunger, means yieldingly restraining such lateral movement of said bearing, a pawl pivotally mounted at one end in said bearing and extending toward said plunger, said plunger having a side surface confronting said pawl 20 when said plunger is intermediate its up and down positions, said bearing being spaced a distance from the plane of said surface less than the length of said pawl, such that the free end of the pawl will engage said surface cant fashion and means yieldingly urging said pawl in position 25 normal to said plunger when said plunger is in its up and down positions.

20 5. A nail driver comprising an elongated body having an upwardly extending head portion at its forward end and a rear portion, said head portion being formed with a nail delivery passage, a magazine receiving chamber extending rearwardly from said head portion to said rear portion, a nail magazine moveable into and out of said chamber and having an elongated nail guideway in registration and communicating with said delivery passage when said magazine is positioned in said chamber, a pusher slidably mounted in said guideway, a spring for urging said pusher forwardly along the guideway toward said head portion to advance a row of nails along the guideway to said delivery passage, said pusher being retractible from said magazine into said rear portion of the body, means carried by said rear portion and movable into engagement with said magazine to retain the same in said chamber, a releasable latch means mounted in said rear portion and movable into latching engagement with said pusher for holding the same in retracted position, said pusher being operable in retracted position to move said magazine retaining means out of engagement with said magazine.

25 6. A nail driver comprising an elongated body having an upwardly extending head portion at its forward end and a rear portion, the intermediate portion of said body being formed with an elongated magazine receiving chamber, said head portion being formed with a nail delivery passage, a nail magazine pivotally secured at its forward end to said head portion for movement about said pivot into said chamber and out of said chamber to loading position, said magazine having a nail guideway aligned and communicating with said nail delivery passage when the magazine is moved into said chamber, a pusher slidably mounted in said nail guideway, and a spring cooperating with said pusher for urging the same forwardly along the guideway toward said head portion to advance a row of nails along the guideway for delivery to said delivery passage, said pusher being retractible from said magazine into said rear portion of the body, said magazine having means operable when the same is moved to outward loading position to prevent forward movement of said pusher from said rear portion of the body.

30 7. A nail driver comprising a body having an upwardly extending head portion at its forward end formed with a nail delivery passage, a magazine structure for feeding nails to said passage, a plunger slidably mounted in the head portion and having a depending nail driving blade 35 for movement downwardly through said passage upon downward movement of the plunger to down position to drive a nail through said passage into a work piece, a spring for effecting an upward return movement of said plunger to its up position, a bearing mounted in said head portion for lateral movement in a direction from said plunger, means yieldingly restraining such lateral movement of said bearing, a pawl pivotally mounted at one end in said bearing and extending toward said plunger, said plunger having a side surface confronting said pawl 40 when said plunger is intermediate its up and down positions, said bearing being spaced a distance from the plane of said surface less than the length of said pawl, such that the free end of the pawl will engage said surface cant fashion and means yieldingly urging said pawl in position normal to said plunger when said plunger is in its up and down positions.
